US0D1051912S

(12) **United States Design Patent** (10) **Patent No.:** **US D1,051,912 S**
Chen et al. (45) **Date of Patent:** **** Nov. 19, 2024**

(54) **DISPLAY SCREEN OR PORTION THEREOF WITH A GRAPHICAL USER INTERFACE**

(71) Applicant: **Anode IP LLC**, Tampa, FL (US)

(72) Inventors: **John Chen**, Tampa, FL (US); **John Erickson**, Chatham, NJ (US)

(73) Assignee: **Anode IP LLC**, Tampa, FL (US)

(**) Term: **15 Years**

(21) Appl. No.: **29/783,149**

(22) Filed: **May 11, 2021**

(51) **LOC (14) Cl.** **14-04**

(52) **U.S. Cl.**

USPC **D14/486**

(57) **CLAIM**

The ornamental design for a display screen or portion thereof with a graphical user interface, as shown and described.

DESCRIPTION

The FIGURE is a front view of a display screen or a portion thereof with a graphical user interface showing our new design.

The outermost broken lines in the drawing illustrate a device that forms no part of the claimed design. The remainder of the broken lines shown in the drawing illustrate portions of the graphical user interface that form no part of the claimed design.

1 Claim, 1 Drawing Sheet
